C. M. CHRISTENSEN.
SHIP'S LOG.
APPLICATION FILED JULY 17, 1920.

1,403,894.

Patented Jan. 17, 1922.

UNITED STATES PATENT OFFICE.

CHRISTEN M. CHRISTENSEN, OF EAST ORANGE, NEW JERSEY.

SHIP'S LOG.

1,403,894.

Specification of Letters Patent. Patented Jan. 17, 1922.

Application filed July 17, 1920. Serial No. 396,929.

To all whom it may concern:

Be it known that I, CHRISTEN M. CHRISTENSEN, a citizen of the United States, and resident of East Orange, in the county of Essex 5 and State of New Jersey, have invented certain new and useful Improvements in Ships' Logs, of which the following is a specification.

This invention relates to improvements in ships' logs. The object of the invention is to provide a generally improved ship's log comprising such novel features and arrangements as are hereinafter set forth and pointed out in the appended claim.

15 The invention will be more fully understood from the following specification taken in connection with the accompanying drawing in which—

Figure 1 is a vertical sectional view, partly broken away, of a ship's log embodying my invention.

Figure 2 is a view in elevation at right angle to the view shown in Figure 1 and with parts broken away.

25 Figure 3 is a transverse sectional view on line 3—3 of Figure 1.

Figure 4 is a diagrammatical transverse sectional view of a vessel showing the ship's log in position.

30 Figure 5 is a fragmentary diagrammatical longitudinal view of the vessel with the ship's log in position.

Referring to Figures 1, 2 and 3 my ship's log comprises an indicator 10 of any usual 35 or suitable construction for giving the correct readings of the speed of the vessel. The indicator is mounted at the top of a tubular casing 11 which extends preferably from the wheel house 12, see Figures 4 and 5, and 40 down through the vessel to the bottom 14 thereof. The bottom of the vessel 13 is apertured as at 16 so that the interior of the casing communicates with the outside of the vessel. The casing may be suitably secured at the bottom as by a flange 15.

45 Within the casing 11 there is provided a weight 17 which is adapted to slide easily up and down in the casing. For the purpose of preventing lateral displacement of the weight within the casing, the latter and the weight are of a non-circular cross section as shown in Figure 3.

The weight is operable by means of a cable 18 which passes over a pulley 19 suitably mounted in the casing at 20. The free end of the cable may be fastened in any

approved manner. The weight is not suspended from the cable 18 but rests by gravity on the inturned flange 21 at the bottom of the casing.

To the bottom of the weight there is secured a bracket 22 in which is mounted a log propeller 23 which actuates the indicator operating rope or flexible shaft 24 by means of the bevel gears 25 and 26. The 65 shaft 24 extends upwardly through the weight through a bore 27 therein and is connected to the indicator in the usual manner, not shown. 28 is the usual governor wheel on the shaft 24. The casing 11 is provided with a suitable door 29 whereby access may be had to the interior of the casing.

Referring to Figure 5 the numeral 30 denotes one of the main bulkheads in the vessel, as for instance the one between the 75 cargo hold and the engine room. The casing 11 may be located with advantage adjacent the said bulkhead in order to avoid breakage.

During operation the speed of the vessel 80 may be read directly by the officer in the wheel house, the indicator being operated in a well known manner by the propeller 23. The location of the propeller below the bottom of the ship renders it less liable to become clogged by seaweed or for other reasons to become inoperative.

The formation of the casing and the weight insures the proper relationship between the propeller shaft and the vessel. 90 For the purpose of repairing or inspection the weight with the propeller may be raised by means of the rope 18, access being had to the interior of the casing through the door 29. The casing may of course be constructed 95 in any approved manner in sections or otherwise to facilitate installation and removal.

I claim:—

A ship's log comprising a vertically disposed tubular casing of non-circular cross section having an open bottom provided with inturned flanges, an indicating device mounted at the top of the said casing, a relatively long weight within the latter, said weight having a cross section corresponding 105 to and fitting within the said tubular casing, a bracket secured to the bottom of the said weight and adapted to pass through the said open end of the said casing, a vertical and a horizontal shaft mounted in said bracket 110 in permanent operating relationship, an indicator propeller mounted on said horizonta-

tal shaft, gears on said shafts for driving the said vertical shaft from the horizontal shaft, there being a vertically disposed aperture formed in the said weight, a flexible shaft passing through the said aperture and connected to the said vertical shaft and the said indicating device for operating the lat-

ter, means for raising and lowering the said weight within the casing, said weight being adapted to rest by gravity on the flanges aforesaid and a door in said casing permitting access to the interior thereof.

CHRISTEN M. CHRISTENSEN.
